UNITED STATES PATENT OFFICE.

FRANK A. EDSON, OF NORMAN, OKLAHOMA, AND BYRON B. CARTER, OF HINSDALE, ILLINOIS.

DRILL.

Application filed April 10, 1922. Serial No. 550,955.

To all whom it may concern:

Be it known that we, FRANK A. EDSON and BYRON B. CARTER, citizens of the United States, and residents, respectively, of Norman, in the county of Cleveland and State of Oklahoma, and of Hinsdale, in the county of Du Page and State of Illinois, have invented a certain new and useful Improvement in Drills, of which the following is a specification.

This invention relates to drills adapted for deep boring or drilling and relates particularly to drills of this type known as core-barrel drills.

Well known examples of drills of this type to which our invention relates are diamond drills, and other rotary drills having "fish-tail" or "rose" bits.

Drills of the type to which our invention relates are constructed and arranged for forming and removing cores of different mineral strata through which holes are bored, thus showing the exact mineral formations at different depths. Such drills are known as core-barrel drills and are mainly used for prospecting purposes, to determine the character and extent of mineral formations and deposits underlying different areas.

When drilling rock or other hard and relatively homogeneous formations, single barrel drills are used almost entirely, but when drilling in soft, soluble, or easily friable materials or deposits, which would disintegrate under the action of the drill and the water used in operating the drill for the purpose of removing the débris, it is practically impossible to obtain a core with a single barrel drill and, when working in material of the character specified, what are known as core-barrel drills are used, drills of this type comprising an outer casing and a core-barrel rotatably mounted within said casing, which will, in most cases, remove at least fragmentary cores, regardless of the character of the deposit through which the drill is working.

Drills of the type and for the purpose specified are provided with passageways extending lengthwise through the same and, in the operation thereof, a continuous flow of water is maintained downwardly through the passageways in the drill rods and upwardly along the outside of the drill casing and drill rods, operating in the first place,

to lubricate the bit of the drill and, in the second place, to carry off the detritus produced in drilling. The combined action of the drill and water frequently disintegrates the soft, soluble and easily friable material not only at the point where the drill is actually operating, but in the sides of the drill holes above the lower ends of the drills, forming enlargements of the drill holes and, in many cases, causing the unsupported earth forming the sides of such enlargements to cave in and to pack around the drill rod or casing, thereby producing binding of the drill, which is often sufficient to prevent its operation and, in some cases, prevents its withdrawal and necessitating its abandonment.

In some cases and with some types of drills, it has been proposed to prevent the formation of such enlargements in the sides of drill holes by the use of mud-laden fluid in the drilling operation, instead of water, the mud-laden fluid used being as thick and stiff as possible consistent with necessary fluidity.

So far as we are aware, however, prior to our invention, mud-laden fluid never has been used in the operation of a core-barrel drill, for the reason that the water passages in drills of this type have been of such small size that they would very quickly become clogged and closed by the deposit of sediment therein, thus preventing the fluid from reaching the drill-bit and preventing the removing of the detritus produced in drilling.

The object of the invention is, therefore, to provide a core-barrel drill adapted for drilling in soft, soluble and easily friable material, specifically a core-barrel drill so constructed and arranged and provided with fluid passageways of such large size throughout, that mud-laden fluid may be used in drilling operations without danger of said fluid passages becoming choked and the supply of fluid for flushing the drill-bits cut off.

To effect the object of the invention, our improved drill comprises the various features, combinations of features and details of construction hereinafter described and claimed.

In the accompanying drawings in which our invention is fully illustrated, Figure 1 is a longitudinal, central sec-

tional view of the lower end of a core-barrel diamond drill embodying our invention and improvements.

Figures 2, 3, 4 and 5 are sectional plan views on the lines 2—2, 3—3, 4—4 and 5—5, respectively, of Fig. 1.

Figure 6 is a detached top plan view of the drill bit.

Figure 7 is an enlarged vertical sectional view of the core lifter ring.

Figure 8 is an enlarged bottom plan view of the drill bit.

Figure 9 is a fragmentary longitudinal, center sectional view of the lower end of the drill illustrating a modification; and

Figure 10 is an enlarged fragmentary view of the inner core barrel, one-half in elevation and one-half in section, illustrating a modification.

In the accompanying drawings, we have for purposes of clear and definite illustration shown our invention and improvements as applied to and embodied in a diamond drill having an inner core barrel. We do not, however, desire to limit ourselves to the particular embodiment of our invention shown, which is merely illustrative, as our invention contemplates equally the use of other forms of bits suitable for the purpose.

Referring now to Figs. 1 to 8 of the drawings, 1 designates the drill rod, 2 the outer casing of the drill, 3 the inner core-barrel, 4 the drill-bit, 5 the drill rod to drill casing coupling, 6 the couplings of the drill casing, 7 the inner core-barrel couplings, 8 the drill-bit coupling, 9 the core lifter ring and 10 the core lifter shell.

Considered broadly, all of the above and foregoing parts are old and well known in the art and as regards their usual features and excepting as hereinafter particularly described and pointed out, may be of any desired or approved construction and will be readily understood by persons familiar with the art without a description thereof in detail.

The drill rod 1, the drill casing and inner core-barrel 2 and 3, and the drill-bit 4 are hollow, the bore of the drill rod 1 being connected with the upper end of the drill casing 2 by passageways 11 formed in the coupling member 5, and formed in the inner wall of the drill bit 4 are recesses 12, which extend from top to bottom thereof and connect the space or passageway between the drill casing 2 and the inner core-barrel 3 with the bore of the drill-bit and also with grooves 13, formed transversely in the cutting face thereof. The fluid for flushing the drill-bit passes downwardly through the drill rod 1, the passageways 11 in the coupling member 5, the space between the drill casing and the inner core-barrel, the holes 12 in the drill-bit, and outwardly through

the grooves 13, returning thence upwardly along the sides of the drill casing and drill rod.

In the practice of our invention, the space between the drill casing and the inner core-barrel is made of such considerable width and the passageways 11 and recesses 12 in the couplings 5 and drill-bit 4 of such large size that they will not become clogged or stopped up by the deposit of sediment there-in in the usual or contemplated operation of the drill.

As shown, the inner core-barrel is mounted within the outer drill casing so as to permit said core-barrel to turn relatively to said drill casing, thus providing for the inner core-barrel remaining stationary during the drilling operation and thereby preventing any grinding action or attrition by said inner core-barrel tending to disintegrate soft, friable cores. Simple means for thus mounting said inner core-barrel is as follows:—The lower end of said inner core-barrel is coupled directly to the core lifter shell 10, the lower end of which is fitted to turn freely in an enlargement 14 of the upper end of the bore of drill-bit and rests upon the shoulder 15 formed at the bottom of said enlargement. Secured to the upper end of said inner core-barrel is a cap 16, formed on which is a tapered bearing projection 17 which engages a corresponding recessed bearing 18 formed in the coupling member 5. The cap 16 is preferably made of steel and to reduce friction and prevent cutting of the bearing, the bearing 18 is preferably formed directly in a plug 19 of bronze or similar metal, secured in a hole formed in the lower end of the coupling member 5. The bearings for said inner core-barrel are adapted to maintain the said core-barrel substantially concentric with the outer core-barrel, thus providing a space of uniform width between the drill casing and the inner core-barrel on all sides thereof, which, as previously stated, will be sufficiently large to permit the use of mud-laden fluid for flushing the drill without danger of its becoming clogged or stopped up by the deposit of sediment therein. We do not, however, desire to limit ourselves to the particular manner of mounting said inner core-barrel, as our invention contemplates any desired or approved means for this purpose.

When a drill casing and core-barrel comprising but single sections are used, the end bearings will be sufficient to support the inner core-barrel centrally of and in desired spaced relation to the drill casing. Where said drill casing and core-barrel comprising a plurality of sections are used, however, we prefer to provide additional supporting means for said inner core-barrel intermediate its ends. As shown, said means are as follows:—The inner core-barrel sections are

connected by the separate coupling members 7, formed on which are fins or ribs 20, which are of such height that said coupling members 7 will fit the bore of the outer core-barrel without binding. To prevent wear on the drill casing sections, separate coupling members 6 are used for connecting the sections thereof, said coupling members being made in the form of bushings threaded into the connected ends of the drill casing sections, said sections being so proportioned and arranged that the inner core-barrel couplings 7 will be positioned inside of the corresponding drill casing coupling members 6, being fitted directly to the bores thereof. With this construction, it is obvious that if wear of said coupling members 6 occurs, they may readily be renewed at slight expense.

In like manner, fins or ribs 21 are formed on the upper end of the core lifter shell 10, which is coupled directly to the lower end of the inner core-barrel, and on the cap 16 on the upper end of said inner core-barrel. Said fins or ribs 21 are primarily for convenience in assembling the drill casing, inner core-barrel, drill-bit and associated parts, being proportioned to guide the projection 17 into its bearing 18, and the lower end of the core lifter shell into the enlargement 14 of the upper end of the bore of the drill-bit when said drill-bit is attached, this being the final step in assembling the drill. Said fins or ribs 21 are so proportioned, however, that in case of excessive wear in the end bearing of the inner core-barrel, they will, by contact with the inner sides of the drill casing, maintain said drill casing and core-barrel substantially concentric.

In order that an accumulation of air, gas or water, under pressure, in the inner core-barrel 3, shall not prevent or interfere with the designed operation of the drill, said inner core-barrel is provided with vent-openings 22 at its upper end. As shown, said vent-holes are formed in the end of the bearing cap 16.

The core lifter ring 9 is of the usual type and will be readily understood by persons familiar with the art without a description thereof in detail.

Instead of forming the core lifter shell 10 as a separate part, our invention contemplates equally forming said lifter shell as an integral part of the drill-bit 4, which is in accordance with long established practice. With this construction the fins or ribs on the lower end of the inner core-barrel are formed on a ring or collar detachably connected to the lower end of said inner core-barrel, said ring or collar comprising a reduced portion at its lower end which fits into the upper end of the core lifter shell, said ring being provided with inner and outer shoulders the lower end of

the inner core-barrel resting on the inner shoulder, and the outer shoulder resting upon the upper end of the core lifter shell.

This modification is shown in Fig. 9 of the drawings, in which 2' designates the drill casing, 3' the inner core-barrel, 4' the drill-bit detachably connected or coupled to the lower end of the drill casing, 10' the core lifter shell formed integral with said drill-bit, 23 a ring or collar secured to the lower end of the inner core-barrel formed on which are guide fins or ribs 21', said ring or collar comprising a contracted portion 24 fitted to the upper end of the core lifter shell 10' and which forms a shoulder 25 on said ring or coupling member adapted to rest on the upper end of said core lifter shell, and said ring or coupling member being also provided with an interior shoulder 26 which defines full engagement of said ring or collar with the inner core-barrel 3'.

Under some conditions of drilling, as when the drill passes from a hard stratum, as rock, into a soft stratum, as oil bearing sand and some shales, the weight of a hard core, previously formed and contained within the drill barrel and the lower end of which has passed above the core lifter, will be sufficient, when the drill is lifted, to crush and disintegrate the lower core section of soft material, thus permitting the recovery of only a very small, if any, core section.

To remedy this condition, we propose to equip the drill with two or more core lifters supported in spaced relation within the core-barrel.

In what we now consider the preferable embodiment of our invention as it relates to this feature, the core lifter shell or shells of the core lifter or lifters, other than the lowermost, form integral parts of the inner core-barrel couplings, all or any desired number of which may be thus equipped with core lifters.

This modification is shown in Fig. 10 of the drawings, in which 3' designates the inner core-barrel, 7' an inner core-barrel coupling, 10' a core lifter shell which forms an integral part of said coupling, 9' the core lifter ring, and 20' fins or ribs formed on said coupling 7' adapted to prevent buckling of the drill casing and core-barrel.

We claim—

1. In a rotary core-barrel drill of the type specified, the combination of an outer drill casing, a core-barrel rotatably mounted within said casing, and a drill-bit detachably secured to the lower end thereof, said drill being provided with flushing passageways comprising a space formed between the drill casing and the inner core-barrel and passageways in the drill-bit formed by recesses in the inner wall thereof which extend from

top to bottom thereof and connect the bore of said drill-bit with the space between the drill casing and inner core-barrel and transverse grooves formed in the face of the drill-bit.

2. A rotary core-barrel drill as specified in claim 1, in which the flushing passageways are of such large size throughout that mud-laden liquid may be used for flushing purposes.

3. A rotary core-barrel drill as specified in claim 1, in which a bearing cap is detachably secured to the upper end of the core-barrel and a core lifting shell is detachably secured to the lower end thereof, and guide fins are formed on said detachable cap and core lifting shell which fit loosely within the drill casing and maintain said casing and inner core-barrel substantially concentric with each other.

4. A rotary core-barrel drill as specified in claim 1, in which both the drill casing and inner core-barrel comprise separate sections coupled together end to end, the means for coupling said sections comprising a separate coupling bushing for coupling adjacent drill casing sections and a separate coupling sleeve for coupling adjacent inner core-barrel sections, the sections of the drill casing

and of the inner core-barrel being so proportioned and arranged that the couplings of the outer drill casing will surround corresponding inner core-barrel couplings, and fins formed on the coupling members of one thereof which extend into close proximity to the opposed surface of the coupling member of the other, providing renewable means for maintaining said drill casing and inner core-barrel in spaced relation and for preventing buckling thereof.

5. A rotary core-barrel drill as specified in claim 1, in which the inner core-barrel comprises separate sections, and a coupling sleeve for coupling adjacent sections thereof, and the core lifting means comprises a core lifting shell which forms an integral part of an inner core-barrel coupling, and a split core-lifting ring of resilient material within said core lifting shell, the contacting surfaces of said shell and ring being correspondingly tapered.

In testimony that we claim the foregoing as our invention, we have hereunto affixed our signatures this 13th day of March, 1922, and 5th day of April, 1922, respectively.

FRANK A. EDSON.
BYRON B. CARTER.
